PUMP AND PRESSURE-REGULATING UNIT

Adolf von Wangenheim, Detroit, Mich., assignor
to Detroit Lubricator Company, Detroit, Mich.,
a corporation of Michigan

Original application November 19, 1942, Serial
No. 466,116. Divided and this application
March 16, 1944, Serial No. 526,751

4 Claims. (Cl. 103—42)

1

This invention relates to new and useful improvements in units for supplying liquor under pressure and more particularly to a combined pump, pressure regulating means and strainer.

An object of the invention is to provide a unit in which the component parts may be readily assembled with accuracy in commercial quantity production.

Another object is to provide a pump and pressure regulating valve which will be quiet in operation.

The invention consists in the improved construction of parts and their cooperative relation to be more fully described hereinafter and the novelty of which will be particularly pointed out and distinctly claimed.

In the accompanying drawings to be taken as a part of this specification, there is fully and clearly shown a preferred embodiment of the invention, in which drawings:

Figure 1 is a view in front elevation of a combined pump, strainer and pressure regulating valve embodying the invention, but with the pump housing cover member in section and showing the regulating valve in longitudinal central section;

Fig. 2 is a view in section on the line 2—2 of Fig. 1;

Fig. 3 is a detail view in section on line 3—3 of Fig. 1, and

Fig. 4 is a detail sectional view on the line 4—4 of Fig. 1.

Referring to the drawings by characters of reference, 1 designates generally a body or housing member having a chamber 2 formed by a cup-like cover member 3 having a surrounding flange 4 which seats in and against the base of an annular recess in a flat chamber wall 5. Extending from the wall 5 and away from the chamber 2, there is a hollow extension 6 having a bore 7 extending longitudinally therethrough. The bore 7 has a cylindrical portion 7^a opening into the chamber 2 through substantially the middle point of the wall 5 and has, intermediate its ends, an enlarged diameter portion 8 and a bearing or guide portion 9 of reduced diameter relative to the diameter of the bore portion 7^a. Within the chamber 2 there is a pump casing 10 having end closure plate members 11, 12 between which there is clamped a hollow annular stator member 13. The end closure member 12 has an external flat face 14 which seats against the flat wall 5. Projecting from the face 14 there is a hollow extension 15 which extends through the bore 7 and fits the guide portion 9. The extension 15, except

2

for its fit in the portion 9, is in circumferentially spaced relation to the wall of the bore 7 so as to provide for liquid flow in the bore 7 around the extension 15. The passageways 16 are provided in the wall of the hollow extension 6 to permit communication between opposite sides of the portion 9. Journaled in the pump casing extension 15 and projecting therefrom, there is a pump drive shaft 17 which extends out of the housing extension 6. Surrounding the shaft 17 and screw-threaded, as at 18, into the outer end of the bore 7, there is a closure member 19 which tightly clamps the marginal edge portion of a sealing member 20 against an outward facing shoulder 21 in the extension 6. The member 20 is preferably of flexibly resilient sheet material, such, for example, as Ameripol having inserted fabric. On the shaft 17 there is a two-part thrust member 22 which has a rotary fit on the shaft 17 and between the parts of which there is tightly clamped the inner peripheral portion of the annular sealing member 20. The thrust member 22 is urged toward the extension 15 by a coil spring 23 which abuts against the closure member 19 and urges the thrust member 22 into rotary sealing engagement with the face of an annular flange 24 projecting concentrically with the shaft 17 and from a collar 25, preferably press-fitted on the shaft 17. The collar 25 is limited against endwise movement toward the thrust member 22 by a split ring or washer member 26 which seats in a circumferential groove 27 in the shaft 17. A thrust washer or bearing pad 28 surrounds the shaft 17 and is positioned between the collar 25 and the end face of extension 15 to take the thrust of spring 23.

The drive shaft 17 extends through the casing 10 in eccentric relation to the internally cylindrical surface of the stator member 13 and is journaled in the end closure member 11. Keyed on the shaft 17 and fitting between the closure members 11, 12, there is a rotor 29 of annular form and concentric with shaft 17. The rotor 29 has tangential engagement with the cylindrical surface of stator 13 as at 30, see Fig. 2. Accurate tangential sliding fit is provided by means of the locating pins 31, 32 which have their longitudinal center lines intersecting an extended line at right angles to and joining the shaft longitudinal center line and the line of tangential contact. The pin 31 fits in a one diameter hole through the closure members 11, 12 and stator 13 but has its end portions, which are located within the closure members 11 and 12, cut or formed to provide a diametrical flat portion which, being transverse to the above mentioned extended line, will

permit slight radial movement of the stator toward and from the rotor. Any such radial movement is, however, prevented after tight tangential contact is obtained and this is accomplished by means of the pin 32 which has a tight fit in alined apertures in the closure members 11 and 12 and also has a tight fit in the bore of a bushing 33, which bore is alined with the closure member apertures. The bushing bore is drilled or formed after the rotor and stator are in tight tangential contact so that no radial play of the stator relative to the rotor is permitted when the pin 32 has been inserted in its locking position. In order to eliminate any possibility of a shifting of the parts 11, 12 and 13 relative to each other, they are frictionally clamped tightly to each other by means of screws 34.

The rotor 29 carries a plurality of radially reciprocal vanes 37 positioned in guide slots which open into annular grooves 36 concentric with shaft 17 and in the opposite faces of the rotor. In the grooves 36 there are ring members 38 which support the inner ends of the vane members 37 and hold them in contact with the eccentric internally cylindrical face of the stator 13. Opening from chamber 2 into the end closure member 11 substantially parallel to the plane of the rotor 29, there is an inlet conduit 39 which terminates adjacent the point of tangential contact 30 and in registry with a cross passage 40 in the stator 13 and the abutting portion of member 11. This cross passage 40 opens into the pump inlet port which is in the form of arcuate recesses 41 in the inner faces of the end members 11, 12 respectively, and which are in registry with the crescent-shaped space between the rotor and the stator. On the opposite side of the point 30 from inlet 41, there is an exhaust or outlet port which comprises arcuate recesses 45 in the members 11 and 12. From the exhaust recess 45 in plate member 12, see Fig. 3, there is an exhaust outlet port 52 which opens through the closure member face 14 into registry with an outlet passageway 53 opening through the flat chamber wall 5 of the housing member 1. The exhaust port or passage 52 is in communication through a conduit 54 with one of the annular grooves 36 so that the vane members 37 are urged by pump pressure against the stator wall.

The pump casing 10 is secured rigidly in position and with the face 14 in tight sealing engagement with the flat chamber wall 5 so that the pump casing seals communication between the bore 7 and the chamber 2. This is accomplished, see Fig. 4, by frictionally clamping the casing 10 to the wall 5 by means of screws 56, the screws 56 being of smaller diameter than the holes 57 through the casing 10 through which the screws 56 pass, so that the extension 15 can be accurately alined with the guide portion 9, thereby eliminating any flexing or setting up of twisting stresses in the casing 10.

Within the chamber 2, there is a strainer member 58 of cylindrical form which fits over the closure plate member 12, which is of somewhat larger diameter than the external diameter of the stator 13 and closure member 11, so as to provide spacing between the pump casing and the internal diameter of the strainer member 58. The housing cover member 3 engages one end face of the strainer member 58 and holds it tightly clamped against the flat chamber wall 5, the strainer member 58 being of an external diameter to provide a clearance space around its external circumference within the cover member 3. This

strainer member may be composed of an inner cylinder of foraminous material 59, such as wire screening, which serves as a base or support for a cylindrical pad of filter material 60. The cover member 3 is tightly clamped and sealed in position against the wall 5 by means of clamping screws 61 which engage the cover member flange 4.

In the housing member 1 there is an inlet passageway 62 which opens through the wall 5, as at 63, externally of the strainer member 58 so that fluid flowing through the conduit 62 must pass through the strainer member 58 in order to reach the pump inlet passageway 39. The inlet conduit 62 may have a pipe or other conduit member 64 secured thereto and leading from a source of fluid supply. The outlet conduit 53 from the pump extends through the wall of the housing 1 and opens, as at 65, into a pressure regulating valve means 66 and particularly into the pressure chamber 67 thereof. The regulating means 66 also includes a by-pass chamber 68 and these chambers 67 and 68 are separated by a pressure responsive member 69, preferably a sheet of flexible, stretchable, resilient material, such, for example, as Ameripol. Between the chambers 67, 68, the housing member has an internal annular shoulder 70, on which the marginal portion of the member 69 seats. A clamping ring and guide member 71 overlies the shoulder 70 and clamps the marginal edge of the member 69 in tight sealing relation thereto. The ring member 71 is held in position by a hollow clamping nut 72 screw-threaded within the chamber 68. Slidably guided within the ring member 71, there is a cup-shaped backing member 73 having its base portion seating on the pressure responsive diaphragm member 69. Through the diaphragm member 69 and the cup member 73 base portion, there is a central alined opening through which there extends a tubular valve seat and guide member 74 having an annular clamping flange which seats against and tightly clamps the diaphragm member 69 to the cup member 73 base portion. The seat member 74 extends through the cup member base portion and is rigidly secured thereto and has a projecting end portion within the chamber 68. Within the cup member 73 and seating on its base, there is a silencer disc member 75 of flexible, stretchable, resilient material, such, for example, as Ameripol and having a small opening 75a therethrough registering with the bore of the seat member 74. This silencer member 75 is held at its marginal edge portion tightly against the bottom of the cup member 73 by a flanged washer 76 having a tight fit in the cup member 73 and by a helical coil spring 77 which seats at one end on the washer 76. The spring 77, at its other end, abuts an adjustment abutment means 78 by which the force of the spring 77 can be adjusted to determine the force acting on diaphragm member 69 in chamber 77, which will move the diaphragm member 69 toward the by-pass chamber 68. Leading from the by-pass conduit 68 through the wall of housing member 1, there is a by-pass conduit 78a, which opens at its outlet end, as at 79, into the bore portion 7a around the extension 15 and between chamber 8 and the valve casing closure of bore 7. The fluid which empties into chamber 8 through conduit outlet 79 is free to pass through a port 80, see Fig. 4, into a passageway 81 which opens at its lower end, as at 82, externally of the housing 1 for connection of a pipe or conduit leading back,

for example, to the source of fluid supply. The other or upper end of this passageway 81 may be closed by a screw plug 83, thereby closing off communication between the passageway 81 and a passageway 84 which opens into the chamber 2, as at 85, see Fig. 4. If desired, the passage outlet 82 may be closed by a plug and the plug 83 removed, so that flow from passageway 81 will pass through passageway 84 into the chamber 2 and return to the pump inlet passageway 39. The pressure chamber 67 has an outlet port or passageway 86 controlled by valve means 87, which is preferably in the form of a double ended valve member also controlling the flow through the seat member 74 into the by-pass chamber 68. The bore of the seat member 74 provided a by-pass outlet from the pressure chamber 67. The valve member end portion cooperable with the seat member preferably has a bleed slot 88, so that any entrapped air or gas will be discharged and not cause the pump to lose its prime or be air bound. The spring 77 urges the seat member 74 into closing relation against the double ended valve member 87 and urges this member 87 into closing relation with the outlet 86. A spring 89 tends to move the valve means 87 into open relation with respect to the outlet 86 and does so move the valve member 87 when pressure in the chamber 67 moves the diaphragm member 69 upward or toward the by-pass chamber 68. A stop member 90 is provided to limit the movement of valve means 87 by the spring 89, so that when the valve means has been opened a predetermined distance, the seat member 74 can thereupon move away from the valve means 87 to open the by-pass port into the by-pass chamber 68. This action of the valve means 87 is well understood in the art and no further explanation is therefore necessary.

The operation of this combined pump, regulating means and strainer unit and of the parts of the same is as follows. It is, of course, assumed that the unit is utilized for supplying oil to an oil burner, for example, so that the outlet 86 is connected to the burner and the inlet conduit 64 is connected to a source of liquid fuel, and the outlet 82 is connected back to the fuel source. When the pump is started oil will be drawn into the chamber 2 through the inlet conduit 62 and through the strainer member 58 and the inlet passageway 39 to the pump inlet ports 41. The rotating vanes 37 will discharge the oil under pressure into the outlet recesses 45 and the outlet 52 and through the restricted port 55 into the outlet passageway 53. Due to the conduit 54, oil will, of course, be held under compression in the annular grooves 36, thereby maintaining the vane members in contact with the cylindrical stator surface.

The oil which is discharged through the passageway 53 will be fed into the pressure chamber 67, see Fig. 1, and when the pressure has built up so that the force exerted against the diaphragm 69 is sufficient to overcome the force of the compression regulating spring 77, then the diaphragm member 69 will be moved toward the by-pass chamber 68, thus permitting the valve means 87 to move toward open position or upward, thereby permitting the discharge of oil through the outlet passage 86 to the burner. When the pump gets up to speed and is discharging out at a rate to create the maximum desired pressure in chamber 67 and at the burner, then, upon any pressure increase, the diaphragm member 69 will move away from the valve means

87, thereby opening the by-pass port through seat member 74. The extent of opening at the valve seat member 74 will, of course, vary with the pressure in chamber 67. The oil discharging into chamber 68 will be fed therefrom through the passageway 78 into the chamber 8 and thence through port 80 to the outlet of passage 81 which leads back to the supply tank. If, as above noted, the outlet 82 is closed by a plug 10 and the screw plug 83 is removed, then this by-pass oil will be discharged through the by-pass 84 back into the chamber 2 for return to the pump.

The silencing feature of the pressure regulating means functions by automatically controlling the flow area of the small opening 75^a. The pressure in chamber 67, which is sufficient to lift the diaphragm member 69, will, if its flow is at a greater rate than can be handled by the small opening 75^a, cause the disc member 75 to stretch upward, thereby increasing the size of the small opening 75^a. Therefore, instead of the oil which discharges through the seat member 75 being sprayed into the chamber 68 with a hissing noise, the oil will be confined by the port or small opening 75^a and be discharged into chamber 68 as a solid stream. It will, of course, be apparent that the size of the opening 75^a will vary automatically, in accordance with the pressure of the liquid against the inlet side of the disc member 75.

This application is a division of my copending application Serial No. 466,116, filed November 19, 1942, for Pump and pressure control means (Patent No. 2,460,047).

What is claimed and is desired to be secured by Letters Patent of the United States is:

1. An apparatus of the character described, comprising a housing member having an end wall and a side wall enclosing a fluid inlet chamber, a fluid inlet to said chamber and a fluid outlet through said end wall, said housing member having a hollow extension from said end wall and a bore through said end wall intercommunicating with said extension and said chamber, a closed pump casing unit in said chamber spaced laterally from said side wall and seating on said end wall, said casing unit having a tubular shaft supporting extension projecting through said bore and spaced for at least a portion of its length from the wall of said hollow extension, a drive shaft extending from and through said tubular extension, means sealing said shaft to said hollow extension, an end wall of said pump casing unit closing off communication between said chamber and said hollow extension, said pump casing unit having an inlet opening into said chamber, said pump casing unit end wall having an outlet registering with and sealed to said chamber end wall outlet, pressure regulating means having a pressure chamber with a valve controlled outlet and a valve controlled by-pass, said pressure chamber communicating with said housing member chamber outlet, a conduit leading from said valve controlled by-pass and opening into the space around said shaft supporting extension, and a by-pass conduit communicating with said space and communicable with said fluid inlet chamber and with a point exterior of said housing member.
2. An apparatus of the character described, comprising a housing member having an end wall and a side wall enclosing a fluid inlet chamber, a fluid inlet to said chamber and a fluid outlet through said end wall, said housing member

having a hollow extension from said end wall and a bore through said end wall intercommunicating said extension and said chamber, a closed pump casing unit in said chamber spaced laterally from said side wall and seating on said end wall, said casing unit having a tubular shaft supporting extension projecting through said bore and spaced for at least a portion of its length from the wall of said hollow extension, a drive shaft extending from and through said tubular extension, means sealing said shaft to said hollow extension, an end wall of said pump casing unit closing off communication between said chamber and said hollow extension, said pump casing unit having an inlet opening into said chamber, said pump casing unit end wall having an outlet registering with and sealed to said chamber end wall outlet, said housing member having a pressure chamber in communication with said chamber end wall outlet and having a by-pass chamber in communication with the space around said shaft supporting extension, a pressure responsive member separating said pressure chamber and said by-pass chamber and having an opening therethrough, said housing member having an outlet from said pressure chamber, valve means controlled by said responsive member and controlling outflow from said pressure chamber through said pressure chamber outlet and through said opening, and means to silence the noise of flow through said opening into said by-pass chamber.

3. An apparatus of the character described, comprising a housing member having an end wall and a side wall enclosing a fluid inlet chamber, a fluid inlet to said chamber and a fluid outlet through said end wall, said housing member having a hollow extension from said end wall and a bore through said end wall intercommunicating said extension and said chamber, a closed pump casing unit in said chamber spaced laterally from said side wall and seating on said end wall, said casing unit having a tubular shaft supporting extension projecting through said bore and spaced for at least a portion of its length from the wall of said hollow extension to provide a by-pass chamber, a drive shaft extending from and through said tubular extension, means sealing said shaft to said hollow extension, an end wall of said pump casing unit closing off communication between said chamber and said hollow extension, said pump casing unit having an inlet opening into said chamber, said pump casing unit end wall having an outlet registering with and sealed to said chamber end wall outlet, pressure regulating means having a pressure chamber with a valve controlled outlet and a valve controlled by-pass, said pressure chamber communicating with said housing member chamber outlet, a conduit leading from said valve controlled by-pass and opening into said by-pass chamber around said shaft supporting extension, and a by-pass conduit opening from the exterior of said housing member and having its inner end communicating with said pump casing unit inlet, a passageway leading from said by-pass chamber

8
ber and opening into said by-pass conduit, and a plug insertable through said by-pass conduit for closing communication between said last-named passageway and said pump casing unit inlet.

5 4. An apparatus of the character described, comprising a housing member having a flat wall portion, a cup-like cover member having its rim secured and sealed to said wall portion to provide a fluid inlet chamber, said wall portion having a hollow extension thereon and having a bore opening therefrom into said chamber and having an inlet and an outlet also opening into said chamber, a pump casing unit in said chamber and having a tubular extension projecting into and spaced for at least a portion of its length from the wall of said hollow extension bore to provide a by-pass chamber, a drive shaft extending from and through said tubular extension, means sealing said shaft to said hollow extension, said pump casing unit having an end wall seating on said flat wall portion to close off communication between said by-pass chamber and said fluid inlet chamber, said casing unit having an inlet opening into said fluid inlet chamber, said casing unit end wall having an outlet registering with and sealed to said chamber wall outlet, a cylindrical strainer surrounding said pump casing unit and separating said chamber inlet from said pump casing unit inlet, said cover member sealing and holding said strainer in position, pressure regulating means having a pressure chamber with a valve controlled outlet and a valve controlled by-pass, said pressure chamber communicating with said housing member chamber wall outlet, a conduit leading from said valve controlled by-pass and opening into said by-pass chamber around said extension, and a by-pass conduit communicating with said by-pass chamber and communicable with said fluid inlet chamber and with a point exterior of said housing member.
